CLAIM

The ornamental design for a massage chair, as shown and described.

DESCRIPTION

FIG. 1 is a front, left, top perspective view of a massage chair showing our new design;

FIG. 2 is a back, right, bottom perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is an enlarged view of the encircled area 9 of FIG. 1;

FIG. 10 is an enlarged view of the encircled area 10 of FIG. 1;

FIG. 11 is an enlarged view of the encircled area 11 of FIG. 1;

FIG. 12 is an enlarged view of the encircled area 12 of FIG. 1;

FIG. 13 is an enlarged view of the encircled area 13 of FIG. 2;

FIG. 14 is an enlarged view of the encircled area 14 of FIG. 2;

FIG. 15 is an enlarged view of the encircled area 15 of FIG. 2;

FIG. 16 is an enlarged view of the boxed area 16 of FIG. 5;

FIG. 17 is an enlarged view of the boxed area 17 of FIG. 6;

FIG. 18 is an enlarged view of the boxed area 18 of FIG. 7;

and,

FIG. 19 is an enlarged view of the boxed area 19 of FIG. 8.

The broken lines shown in the figures depict portions of the massage chair that do not form part of the claimed design. The dot-dash lines depict the enlarged view boundaries that do not form part of the claimed design.
